(57) CLAIM

The ornamental design for a men's athletic short, as shown and described.

DESCRIPTION

FIG. 1 is a front perspective view of a men's athletic short, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2;

FIG. 11 is a partial enlarged view of FIG. 2;

FIG. 12 is a partial enlarged view of FIG. 4;

FIG. 13 is a partial enlarged view of FIG. 5;

FIG. 14 is a partial enlarged view of FIG. 5;

FIG. 15 is a partial enlarged view of FIG. 7;

FIG. 16 is a partial enlarged view of FIG. 7; and,

FIG. 17 is a partial enlarged view of FIG. 7.

The dash dot-dot lines in the figures are for the purposes of illustrating portions of the men's athletic short, which form no part of the claim design.

The evenly spaced dash lines in the figures notating enlarged views of the men's athletic short form no part of the claim design.

1 Claim, 10 Drawing Sheets
